UNITED STATES PATENT OFFICE.

GEORGE J. DYSINGER AND MARGARET M. HARRIS, OF MOUNT VERNON, OREGON.

BRUSH ATTACHMENT FOR CLOTHES-WASHING MACHINES.

1,318,984.

Specification of Letters Patent. Patented Oct. 14, 1919.

Application filed July 8, 1919. Serial No. 309,363.

To all whom it may concern:

Be it known that we, GEORGE J. DYSINGER and MARGARET M. HARRIS, citizens of the United States of America, residing at 5 Mount Vernon, in the county of Grant and State of Oregon, have invented certain new and useful Improvements in Brush Attachments for Clothes-Washing Machines, of which the following is a specification.

10 The primary object of the invention is a provision of a brush attachment adapted for securing in any form of clothes washing machine whereby the goods, such as light and heavy articles, are more quickly and easily 15 cleaned by the agitating or pounding means employed.

A further object of the invention is to provide clothes cleaning brushes in an expandible structure adapted to be secured in 20 adjusted position within wash tubs of different forms and dimensions and forming part of a washing machine or apparatus.

A still further object of the invention is to provide coöperating brush members removably positioned in different planes within a washing machine tub in a stationary manner and adapted to coöperate with a movable brush or dasher member in operating upon the clothes during the washing operation.

With these general objects in view the invention consists of the novel combination and arrangement of parts hereinafter fully described in connection with the accompanying drawings and in which like reference characters designate corresponding parts throughout the several views.

In the drawing,

Figure 1 is a vertical sectional view 40 through the invention;

Fig. 2 is a horizontal sectional view taken upon line II—II of Fig. 1;

Fig. 3 is an enlarged sectional view 45 through a portion of the tub showing the adjusting means for the side brushes of our attachment; and

Fig. 4 is an elevational view of a dasher of a form preferably employed with the invention.

50 Referring more in detail to the drawing, the invention as herein illustrated attached to a tub 10 formed of wood and churn shaped with a circular bottom 11 and a contracted upper rim or edge 12, although it 55 will be understood that the invention is equally serviceable in any other form of

wooden or metal tub such as those provided in different makes of washing machines.

A plurality of galvanized iron hoops 13 have brushes 14 transversely secured to the inner side thereof in any suitable manner, such as by the employment of screws 15 which are rust proof, six brushes being herein shown connected together by the hoops 13. These hoops with their brushes 14 are 65 adapted for seating within the tub 10 with the hoops 13 closely engaging the inner face of the tub and the lower ends of the back members 16 of the brushes 14 resting upon the tub bottom 11.

The hoops 13 have lap joints formed of interlocking corrugated end portions 17 adapted for engagement with each other at the side of the tub when the hoops 13 are outstretched firmly engaging the inner surface of the tub, rust proof screws 18 being positioned through the hoop ends 17 and screwed into the adjacent side of the tub.

The hoops 13 and brushes 14 in this manner form a frame adjustable in size for securing within tubs of different dimensions it being understood that in a metal tub bolts or rivets may take the place of the screws 18. An X-shaped brush 19 has its back 20 centrally secured upon the bottom 11 within the 85 tub 10 by means of rust proof screws 21 and whereby the brush 19 coöperates with the side brushes 14 during the clothes washing operation no matter what form of agitator or manner of washing machine is employed.

A disk or dasher of the form illustrated in Fig. 4 of the drawing is preferable, consisting of a circular disk 22 of a form thicker at the center and beveled toward its periphery with a handle 23 projecting centrally therefrom. Brushes 24 in the form of a cross are provided upon the lower convex space of the dasher disk 22 being slightly inclined toward the center of the disk in accordance 100 with beveled lower face thereof.

The complete operation of the invention will be fully understood from this detailed description thereof, the dasher being operated by its handle 23 within the tub 10 will 105 agitate the clothes or articles to be washed within the tub bring the same in forcible scrubbing contact with the brushes 14 and 19 as well as the brushes 24 of the dasher, thereby providing the advantages of a wash 110 or rubbing board and easily and quickly cleaning the article. While the form of the

invention herein set forth is believed preferable, it will be understood that minor changes may be made in the form thereof without departing from the spirit and scope 5 of our invention as claimed.

What we claim as new is,

1. An attachment for washing machines comprising extensible hoops having adjustable overlapping ends, securing means 10 for the hoops extending through said ends when the device is in use, and a plurality of spaced brushes transversely secured upon the inner sides of the hoops with the bristle portions of the brushes radially projecting inwardly of the hoops.
- 15 2. In combination with a circular tub, a

plurality of parallel hoops mounted in the tub firmly engaging the side thereof and having corrugated overlapping ends, securing means through said ends engaging in 20 the side of the tub when the hoops are adjusted therein, a plurality of brushes positioned upright in the tub, with the ends of the backs of the brushes seated upon the bottom of the tub and the bristle portions of 25 the brushes inwardly projecting radially of the tub.

In testimony whereof we affix our signatures.

GEORGE J. DYSINGER.
MARGARET M. HARRIS.
